UNITED STATES PATENT OFFICE.

JONAS A. SPARKS, OF ELK CITY, KANSAS.

APPARATUS FOR CLEANING GASOLINE

Application filed September 22, 1922. Serial No. 528,651.

To all whom it may concern:

Be it known that I, JONAS A. SPARKS, citizen of the United States, residing at Elk City, in the county of Montgomery and State of Kansas, have invented certain new and useful Improvements in Apparatus for Cleaning Gasoline, of which the following is a specification.

This invention relates to an apparatus for cleaning gasoline, being particularly designed for use in dry cleaning establishments for cleaning gasoline used in the dry cleaning of apparel.

As is well known, a quantity of gasoline, after having been used for cleaning clothes not only becomes dirty but also becomes rancid and acquires an offensive odor due to the fatty substances taken up by the gasoline in the cleaning process. A quantity of gasoline can, therefore, only be used for a limited time and the expense of providing fresh gasoline is consequently considerable. The present invention accordingly seeks, as one of its principal objects, to provide an apparatus for cleaning gasoline whereby the gasoline may be easily and quickly cleaned at moderate cost.

Other and incidental objects will appear hereinafter.

30 In the drawing:

Figure 1 is a side elevation of my improved apparatus,

Figure 2 is a fragmentary vertical sectional view through the device, and

35 Figure 3 is a fragmentary section showing the mounting of the sight glass of the device.

In carrying the invention into effect, I employ a preferably cylindrical tank or container 10, which is open at its upper end and is formed at its lower end with a conical bottom wall 11 providing a cleaning charge chamber 12. Connected to the tank at the upper end of said chamber is a suitable draw-off cock 13 above which is a second draw-off cock 13' while at the apex of the bottom wall is mounted an appropriate drain cock 14. Suitably mounted upon the tank adjacent the draw-off cock is, as shown in Figures 1 and 3, a vertically disposed sight glass 15 having its lower end terminating at the upper end of the charge holding chamber 12. Removably supporting the tank is a stand comprising a plurality of uprights 16 connected medially by an annulus 17 below which the uprights are de-

flected outwardly in diverging relation to form legs 18. Connecting the uprights at their upper ends is a second annulus 19 and formed on the tank at its upper end is an overhanging annular lip or flange 20 resting upon said annulus sustaining the tank upon the stand.

Snugly but slidably fitting in the upper end of the tank 10 is a gasoline container 21 provided at its upper end with an annular lip 22 resting upon the lip 20 of the tank sustaining the container and leading downwardly within the tank from the bottom of said container is a relatively small discharge pipe 23. This discharge pipe extends axially of the tank to a point near the lower end of the charge holding chamber 12 and mounted upon said pipe is a circular reticulate strainer 24 snugly fitting within the sloping bottom wall of the tank to provide a partition dividing the charge holding chamber. The strainer is preferably provided with minute openings and rising from the strainer is an annular flange 25 flared to fit at its upper margin against the bottom wall 11. In order to obtain this condition the flange is given a different taper than the conical bottom wall 11. The flange will thus be spaced from the latter entirely except along its upper margin or edge. This has the advantage that grit that might have collected on the conical wall will not prevent the correct positioning of the strainer in the bottom of the container. Closing the container 21 is a removable cover 26 having a depending annular flange 27 snugly fitting within the chamber and provided with an annular lip 28 at the base of said flange to rest upon the lip of the container sustaining the cover.

In use, the chamber 12 of the tank 10 is first filled with a suitable alkali charge. Preferably, a bleacher is added to the charge, as well as a disinfectant and an appropriate deodorant, the charge being of a strength sufficient to operate at about 100° F. The gasoline to be cleaned is then introduced into the container 21 when the cover 26 is applied. Thus, the gasoline will flow from the container 21 through the pipe 23 into the chamber 12 when the gasoline will, being of lighter specific gravity than the cleaning charge, filter upwardly through the charge and percolate through the strainer 24 to finally collect within the tank at the top of the charge. Since the pipe 23 is rel-

tively small while the strainer 24 is also provided with small openings, the flow of gasoline into the chamber 12 and the filtering of the gasoline up through the charge will be correspondingly slow so that the alkali charge will be permitted to act upon the gasoline for effectually emulsifying the fatty substances contained in the gasoline. Furthermore, since the gasoline must percolate through the strainer 24, the gasoline will be divided up into a number of fine streams by the strainer so that the alkali charge can efficiently act thereon. As will be noted, a dead air space is defined within the tank 10 between the lower end of the container 21 and the surface of the charge and it has been found, in practice, that the presence of this dead air space tends to facilitate the dissemination of the gasoline through the charge. The emulsified fatty substances separated from the gasoline will, of course, collect upon the surface of the charge while the gasoline will raise within the tank 10, as it is filtered through the charge, and thus collect above the impurities removed therefrom. Accordingly, by opening the cock 13, the cleaned gasoline may be drawn off and, of course, the sight glass 15 is provided so that the level of the cleaned gasoline may be readily ascertained. Should the gasoline at the level of the cock 13 not be clear, the cock 13' may be used for drawing off clear gasoline at the higher level. Coincident with the removal of the fatty substances from the gasoline, the gasoline will, as it filters through the charge, be disinfected,

bleached and deodorized by the disinfecting, bleaching and deodorizing agents of the charge, as well as impregnated with the alkali ingredients of the charge, so that the final cleaned product will be fresh, clear and free of any undesirable impurities as well as free of the usual strong petroleum smell. Further, the cleaned gasoline, being impregnated with alkali, will be rendered more efficacious for cleaning purposes.

Having thus described the invention, what is claimed as new is:

In a fluid cleaning apparatus, a substantially cylindrical tank having an elongated conical bottom wall, a drain cock at the apex of said bottom wall, a container fitting telescopically in the cylindrical part of said tank and provided with a discharge pipe extending downwardly to within a short distance of said apex, a percolating strainer surrounding said pipe, an upturned flange on said strainer of different taper to said conical bottom wall and adapted to contact therewith along its top edge, and means for suspending said tank a suitable distance above the ground to permit its complete draining through said cock; said means including uprights, upper and lower annular bands connecting said uprights, said tank having an annular flange adapted to rest upon the upper of said annular bands, the lower ends of said uprights forming legs.

In testimony whereof I affix my signature.

JONAS A. SPARKS. [L. s.]
